Fig. 2.

UNITED STATES PATENT OFFICE.

PHILO A. ORTON, OF CHICAGO, ILLINOIS, ASSIGNOR TO ORTON CRANE & SHOVEL COMPANY, OF HUNTINGTON, INDIANA, A CORPORATION OF INDIANA.

DIPPER-OPERATING MECHANISM FOR EXCAVATING MACHINES.

Application filed June 28, 1924. Serial No. 722,891.

This invention relates to dipper operating mechanism for excavating machines or shovels, and relates particularly to such mechanism designed for use on shovels in which internal combustion engines are used as a source of power, although equally adapted for use on any type of machine not equipped with independent power means on the boom for advancing the dipper.

10 For purposes of convenient reference, the machine to which my improved crowding mechanism is applied will be designated a shovel.

As regards its general structural features and method of operation, a shovel embodying my invention and improvements is of the familiar type comprising an under frame supported on wheels, a superstructure rotatably mounted thereon, a supporting boom pivoted to said superstructure so that its outer end may be raised and lowered, and a dipper mounted on said boom by means of its handle so that it will admit both of pivotal and endwise movement thereon. Specifically and in accordance with common practice, the dipper is mounted on the boom by means of a rack on the dipper handle, the teeth of which intermesh with the teeth of a pinion secured to a shaft mounted in bearings on the boom and held in engagement therewith by means of a yoke constructed and arranged to permit endwise movement of said dipper handle to advance and retract the bucket of the dipper.

35 In accordance with accepted practice, also, shovels of the type specified are equipped with means positioned on the boom commonly known as "crowding" means, designated and adapted for advancing the dipper to prevent the bucket from backing or being forced out of the material being excavated as said dipper is turned pivotally to raise it along the face of the excavation to fill the dipper.

40 As regards the dipper operating mechanism, my invention has particular reference to shovels in which the crowding means comprises a shaft rotatably mounted adjacent the pivoted end of the shovel boom, which has driving connection with the power unit of the shovel, and the transmission means connecting said driven shaft to said dipper actuating gear comprises gears mounted on said driven shaft and normally free to turn thereon, and independently operated fric-

tion clutches adapted for separately securing said gears to said shaft.

The invention also has particular reference to crowding means of the type specified, where the power unit of the shovel consists of an internal combustion engine.

Heretofore, so far as I am aware, the transmission means connecting said driven shaft with the dipper actuating gear have been positive—excepting for the friction clutches on said driven shaft. This is objectionable for the reason that it not infrequently results in overloading and "killing" the engine—where the power unit consists of an internal combustion engine—which can only be avoided by close attention on the part of the operator and almost continual manipulation of the main clutch by alternately throwing it into full engagement to secure desired crowding action, and partly releasing it to permit slippage. This tends to produce a jerky crowding action and also results in excessive wear in the clutch, necessitating replacement of the clutch at relatively short intervals, causing direct loss both in labor and money for making replacements and also putting the shovels out of commission while repairs are being made, which often represents indirectly, a much larger loss.

The object of the present invention is to overcome the foregoing objectionable feature and, to this end, the invention consists in introducing a slip-friction device in the transmission connecting the driven shaft with the dipper actuating gear on the boom, the relation being such that slippage will occur in said slip-friction before the load on the engine becomes sufficiently great to kill the engine, thus obviating all necessity for manipulating the main driving clutch on the driven shaft.

Dipper operating mechanism of my invention also comprises the various other features and details of construction hereinafter described and claimed.

In the accompanying drawings, in which my invention is fully illustrated,

Figure 1 is a side view of a shovel boom showing the dipper mounted thereon in operative position, together with crowding mechanism therefor embodying my invention and improvements.

Figure 2 is a top plan view of said boom

with the dipper removed so as to better expose the crowding mechanism; and

Figure 3 is an enlarged sectional view on the line 3—3 of Fig. 2.

5 As regards its general features and excepting as to features hereinafter particularly described and pointed out, a shovel embodying my invention and improvements may be of any approved or desired construction. A considerable number of different makes of shovels of the general type specified are for sale commercially and in common use, and it will not therefore be necessary to show or describe the same in detail, 10 as all necessary details—both as regards structure and operation—can be readily supplied by engineers and mechanics skilled in the art and, in the drawings, I have shown and will describe only the boom and 15 dipper of a shovel equipped with my improved crowding device and which exemplify any usual boom and dipper of this type to which said device may be applied.

Describing my invention with particular 20 reference to the drawings, A designates a shovel boom as a whole, consisting of spaced, rigidly connected members a, a' ; and B designates the dipper as a whole, comprising a usual bucket b and a dipper handle b' mounted between the boom members a, a' . The dipper is supported by means of a rack 1 on the underside of the handle b' , the teeth of which intermesh with the teeth of a pinion 2 secured to a shaft 3 mounted in 25 bearings formed in sleeves 4, 4' secured in brackets 5, 5', on the boom members a, a' , said rack and pinion being maintained in engagement with each other by a yoke 6, in accordance with usual practice.

40 In accordance with my invention, rotation is adapted to be imparted to the pinion shaft 2 from a counter shaft 7, mounted in bearings in sleeves 8, 8' secured in the brackets 5, 5', by means of a friction transmission gear as follows:—Mounted to turn on an end of the counter shaft 7, which projects through the boom member a' is a pinion 9 formed on which are disks or cheek plates 10, 10' and splined or otherwise secured to said counter shaft at opposite sides of said pinion so as to rotate therewith while, at the same time, permitting endwise movement thereof on said shaft, are friction disks or plates 11, 11', which are adapted to be maintained in strong frictional engagement with the cheek plates 10, 10' by a spring 12 inserted between the face of the hub of the friction plate 11' and a rigid abutment or shoulder 13 on a sleeve 14 secured in position on the end of said counter shaft by a nut 15 threaded to the outer end of said counter shaft. The thrust of the spring 12 is sustained by the bearing sleeve 8' against which the face of the hub of the friction plate 11 abuts. Obviously, the frictional engagement of the pinion 9 may be adjusted as desired by turning the nut 15 to either increase or decrease the tension of the spring 12.

The friction faces of the disks or plates 11, 11', are lined with suitable material, as indicated at 16, secured thereto by copper rivets or other suitable means, which may be renewed as they become worn, thus extending the life of said friction disks almost indefinitely. Preferable material from which to make the lining 16 is the product known commercially as asbestos fabric.

Ribs or webs 10² preferably connect the cheek plates 10, 10', with their hubs, operating both to strengthen and stiffen said cheek plates and also providing a large radiating area which will tend to prevent the friction linings from burning out in operation.

80 The pinion shaft 3 is driven by a gear 17 secured to the projecting end thereof, which meshes with the pinion 9 on the counter shaft 7.

85 The counter shaft 7 is adapted to be rotated in opposite directions—as it is desired to advance or retract the dipper—by driving connection with a shaft 18, consisting of a shaft 19 which extends lengthwise of the boom A and is rotatably mounted in brackets 20, 20', secured, respectively, to the upper edges of the boom members a, a' , adjacent to said counter shaft, and to transverse members 21, 21' secured to the upper and lower edges of said boom members adjacent to the pivoted end or foot of the boom. Secured to the inner end of the shaft 19 is a bevelled gear 22 which meshes with bevelled gears 23, 23' on the shaft 18, and secured to the outer end of said shaft 19 is 100 a bevelled gear 24 which meshes with a bevelled gear 25 secured to rotate with the counter shaft 7. As shown, all of said gears are 105 mitre gears.

110 The gears 23, 23' are normally loose on the shaft 18 and are adapted to be secured thereto so as to rotate therewith by means of suitable clutches indicated at 26, 26', engagement and disengagement of which with said gears is adapted to be effected by means 115 controlled by the shovel operator, in a usual manner.

120 As shown, the clutches 26, 26' are a usual type of cone friction clutch, the male members or cones of which are splined to the shaft 18 and the female members of which are formed directly in the hubs of the gears 23, 23'. Said clutches are adapted to be separately engaged to cause the corresponding gear 23, 23' to rotate with the shaft 18, to 125 either advance or retract the dipper, as the case may be, by means of cam-collars 27, 28, 27', 28', mounted on said shaft 18, the collars 27, 27' bearing directly against the ends of the male members of said clutches and being 130

held against rotation by engagement with a rock shaft 29, and the collars 28, 28' having arms 30 formed thereon which are connected by links 31 with arms 32 secured to said rock 5 shaft. Said cam collars are provided on their contacting faces with engaging cam surfaces, the cam surfaces on the collars 27, 28 being oppositely inclined to those on the collars 27', 28', whereby, when the rock 10 shaft is turned in one direction or the other, one or the other of the clutches 26, 26' will be thrown into engagement to turn the shaft 19 in a direction to either advance or retract the dipper as may be desired.

15 The rock shaft 29 is adapted to be controlled by the shovel operator by suitable lever connections, not shown.

The thrust of the cam collars 27, 28, 27', 28' is sustained by nuts threaded to the shaft 20 18, said nuts being preferably slotted and adapted to be clamped in any desired adjusted position thereon by clamping screws applied to the slotted portions thereof.

I do not, however, desire to limit myself 25 to any particular form of clutch and clutch operating mechanism, as my invention contemplates the use of any desired or approved form of clutch and operating means, such as skilled mechanics could readily supply and 30 of which the clutches shown are merely an exemplification.

The counter shaft 7 is preferably equipped with a brake, indicated at C, controlled by the shovel operator through suitable lever

connections provided for the purpose, not 35 shown, and which provides means for holding the dipper in any desired position. Said brake may be of any desired or approved type and can readily be supplied by skilled mechanics and will not, therefore, be either 40 shown or described in detail.

By properly adjusting the tension of the spring 12 which controls the frictional engagement of the pinion 9 with the counter shaft 7, it is obvious that, by throwing in 45 proper clutch 26, 26' to rotate the shaft 3 in a direction to advance the dipper B, said dipper will be forced or crowded into the bank as the dipper is raised along the face of an excavation to fill the same, all in the manner desired and contemplated.

I claim—

Operating mechanism for shovels of the type specified, comprising in combination, a shaft adapted to be rotated continuously in 55 operation by driving connection with a prime mover, dipper supporting and actuating means, and transmission means connecting said driven shaft and dipper supporting and actuating means, comprising manually controlled friction clutches on said driven shaft, and a slip-friction transmission device applied intermediate said clutches and the dipper supporting and actuating means.

In witness that I claim the foregoing as 65 my invention, I affix my signature this 7th day of June, A. D. 1924.

PHILO A. ORTON.
